[57] CLAIM

The ornamental design for a front portion of a kitchen hood, as shown and described.

DESCRIPTION

FIG. 1 is a perspective view of the front portion of a kitchen hood;

FIG. 2 is a front view of the front portion of a kitchen hood of FIG. 1;

FIG. 3 is a plan view of the front portion of a kitchen hood of FIG. 1;

FIG. 4 is a right elevation view of the front portion of a kitchen hood of FIG. 1;

FIG. 5 is a bottom view of the front portion of a kitchen hood of FIG. 1;

FIG. 6 is a perspective view of the front portion of a kitchen hood showing a second embodiment of our new design;

FIG. 7 is a front view of the front portion of a kitchen hood of FIG. 6;

FIG. 8 is a plan view of the front portion of a kitchen hood of FIG. 7;

FIG. 9 is a right elevation view of the front portion of a kitchen hood of FIG. 7; and,

FIG. 10 is a bottom view of the front portion of a kitchen hood of FIG. 7.

The broken line showing of environmental structure is for illustrative purposes only and forms no part of the claimed design.
